VOICE OPERATED SWITCHING

Edward K. Sandeman and Frederick G. Filby,
Aldwych, London, England, assignors to International Standard Electric Corporation, New York, N. Y., a corporation of Delaware

Application January 23, 1931, Serial No. 510,617,
and in Great Britain February 12, 1930

6 Claims. (Cl. 178—44)

This invention relates to switching arrangements for use in electric signalling systems.

It is known that in certain types of signalling systems it is often required to perform switching operations either before or after the signals are transmitted. For instance in a telephone system it is necessary to actuate a number of switching devices so that a suitable circuit is provided for transmitting a given signal to the desired station. Sometimes it is also required to select a given path amongst a plurality of paths leading from the transmitting station to the receiving station.

The switching operations above mentioned may be performed either manually as in manual systems (telephone systems, telegraph systems etc.,) or by the intermediary of auxiliary signals sent by mechanically actuated apparatus such as for instance the dial impulses or switchhook impulses used in automatic telephone systems.

It will be clear that the systems referred to necessitate mechanical actuating to perform the required switching operations.

An object of the present invention is to provide an improved arrangement in a signalling system wherein a number of operations such as switching operations may be efficiently performed entirely under the control of the main signals.

According to one feature of the invention means are provided for sending an auxiliary signal or pulse entirely under control of the main signal at the cessation of transmission of the main signal. This auxiliary signal or pulse is adapted to change or allow to be changed the direction in which the system is conditioned for transmission.

According to another feature of the invention means are provided for sending a preliminary pulse or signal for conditioning for reception the apparatus of the station to which the transmitted signal is intended to be sent and a following pulse or signal for restoring to normal the apparatus of said station, said auxiliary pulses or signals being sent entirely under the control of the main signals.

According to another feature of the invention the preliminary and/or following pulse as above may be in the form of a code.

Other features of the invention will be apparent from the following description with reference to the accompanying drawings of which:

Figs. 1A and 1B show terminal equipment for use in connection with a radio link in which the radio transmitter and radio receiver are indicated by RT and RR respectively.

Figs. 2A and 2B are schematics of the circuits

for use at intermediate stations of a submarine cable or other two wire circuit.

Fig. 3 shows the form of the impulses used to actuate certain relays.

Fig. 4 shows a modification of the circuit when used at submarine cable terminations.

Referring to Fig. 1A of the drawings, assume that speech arrives over the line at W—E. The speech actuates the detector amplifier R₁, the output of which is connected through the quick operate—quick release relay E and the slow operate—slow release relay F. The operation of the relay E causes contact E₃ which is normally broken, to close. This puts earth on relay G through contact F₂ of relay F which is normally closed. The operation of relay G causes contact G₂ to close, connecting the oscillator O₁ to the line. Thus the coded signal is sent into the radio transmitter and this continues until the operation of relay F causes the contact F₂ to break. The breaking of this contact allows relay G to release and the pulse to cease. The generation of the "following" pulse is caused when the output from R₁ ceases. This releases relays E and F causing contact E₂ to make, which puts earth through contact F₅ of relay F, to relay H. The operation of relay H closes the contact H₁ and the oscillator O₂ is put on to the line through a delay network D₂. The pulse continues until slow release relay F allows contact F₅ to break. The amplifier A prevents the "following" pulse from acting back through the delay network D₁ and operating the detector amplifier R₁. The purpose of the delay network D₁ is to hold up the speech whilst the "preliminary" pulse is sent out, and its delay must be equal to the time of operation of relay F. The network D₂ delays the "following" pulse until the last of the speech has passed through D₁ into the transmitter, and its delay should be equal to delay D₁ minus (the time of release of E plus the time of operation of H). D₁ and D₂ have been shown in the diagram as two separate networks, but it is possible to dispense with D₂ and bridge the oscillator O₂ across two points in D₁ in such a way that the above condition is fulfilled. O₁ and O₂, have in the above, been referred to as oscillators but it should be understood that in general, these represent any method of generation of the desired form of coded signals.

The arrangements at the "receiving" end (E—W in Fig. 1B) are as follows:—The detector amplifier R₂ is tuned to the oscillator O₁, and its output causes relays J and K to operate. The operation of relay J breaks contact J₁ and, there-

fore, the output circuit of the detector amplifier R_3 , which is tuned to receive the "following" pulse. The relay K in conjunction with relays L , M and N form a selective relay arrangement by means of which the particular code which is being used is picked out. The operation of this chain of relays will be described later. When the pulse causes this relay arrangement to operate, relay N causes contacts N_6 and N_8 to break, thus removing earth from the two slow release relays S and P . Unless the pulse is of a sufficient predetermined length the relays P and S will not release. If, however, P releases, earth is connected to relay X through contact P_1 causing X to operate. This switches the line into the "receive" position. X also closes contact X_1 , putting earth through contacts T_1 and S_1 on to itself, thus locking the circuit. If the pulse is of greater length than the predetermined value, the relay S will also release, thus breaking contact S_1 and preventing the circuit from locking. When speech has ceased and the "following" pulse arrives, the output from R_3 operates relay Q through contact J_1 and by an arrangement of relays U , W and Y , similar to L , M and N , but arranged to receive the code of the "following" pulse, causes contacts Y_1 and Y_2 to break. If the pulse is again of sufficient length this allows slow release relay T to release, thus breaking contact T_1 and taking earth off relay X allowing the contacts to fall back into the "transmitting" position. If however, the pulse is too long, relay V will also release and contact V_1 will make. This shorts contact T_1 of relay T and prevents relay X from releasing. It should be noted that the difference of the release times of T and V should be less than the release time of X .

In general, the two pulses will be both different in code and in length. For example, in a particular case the "preliminary" pulse might be 2,000 c. p. s. interrupted 25 c. p. s. lasting for 120 milliseconds whilst the "following" pulse is 500 c. p. s. interrupted 15 c. p. s. for 200 milliseconds. In this case, the form of the rectified impulses acting on relays K and Q is as shown in Fig. 3 of the drawings

In the first case

$$AB=BC=CD=DE=EF=20 \text{ milliseconds},$$

whereas in the second case

$$AB=BC=CD=DE=EF=33 \text{ milliseconds},$$

The way in which the selectively relay arrangements operates is as follows:—

Taking the example of a preliminary pulse given above it is necessary that this pulse shall operate the train of relays K , L , M , and N .

Suppose the "operate" and "release" times of these relays are

- 60 K , operate time 2 millisecond, release time 3 milliseconds
- 61 L , operate time 2 millisecond, release time 19 milliseconds
- 62 M , operate time 2 millisecond, release time 17 milliseconds
- 63 N , operate time 2 millisecond, release time 4 milliseconds

Now when impulses as described above energize K , it will be alternately operated and released for periods of 21 and 19 milliseconds respectively. The operation of K removes earth from relay L and also operates relay N . After 19 milliseconds L will release taking earth off N and energizing relay M . Two milliseconds later M operates and

K releases, thus taking earth off M and again energizing N . After 17 milliseconds M releases taking earth off N and energizing L and after a further two milliseconds L and K again operate once more energizing N . These operations are then repeated as long as the pulse continues.

During the above process relay N remains continuously operated, for at no time is the current cut off for a period as great as its release time and hence if the length of the pulse is greater than the release time of relay P but less than that of S , then the switching will be accomplished.

Obviously the arrangement may be used for other codes if relays of appropriate operate and release times are employed.

In the case of an intermediate station the arrangements are very similar to the above except that the "receiving" arrangement, as well as switching the circuit by means of relay X , generates a fresh pulse which proceeds to the distant end of the circuit. This is done by placing the two relays E and F in circuit with the relay X as shown in Fig. 2A and Fig. 2B. These figures show an arrangement for use at an intermediate station, the reference characters being the same as in Fig. 1A and Fig. 1B. A_1 , A_2 , A_3 , A_4 , A_5 and A_6 represent the necessary amplifiers, and D is a delay network which holds up the speech while the switching is performed. The generation of the pulse is exactly similar to the previous case. In this case the relay X should be a quick operate-slow release relay to allow the "following" pulse to pass the switch before the line returns to the "transmitting" position.

In the case of the terminal equipments for a submarine cable or other two wire circuit which is terminated in a four-wire line a further modification is necessary to remove any possibility of a lock-up if pulses are sent from the two ends simultaneously or within a period equal to the transmission time of the circuit. This modification consists in placing a quick-operate relay in the output circuit of the amplifier detector in the pulse generating arrangement at one end. The operation of this relay breaks the input circuit of the pulse receiving apparatus at that end. Fig. 4 illustrates this case and the reference characters are as in Figs. 1A, 1B, 2A and 2B. Thus, in the figure, for example, if signals are originated simultaneously at the two ends of the circuit switching will only be effected at the E — W end, the W end pulse receiving apparatus being disabled by the relay Z . For simplicity only one set of pulse generating apparatus has been shown in detail in Fig. 4, the complementary generating and receiving apparatus being shown as blocks and designated FRA and PGA . $S.C.$ represents a submarine cable.

In order to prevent false operation of the system due to momentary cessation or reduction in strength of the signal it may be necessary to introduce a delay in the disabling or changing of the transmitting direction of the system. This can be done conveniently by making the relays K and S operating from detector-amplifier R_2 and relay Q operating from detector-amplifier R_3 sluggish in operation. Alternatively, of course, any suitable form of relay train may be added in place of these relays.

What is claimed is:

1. In an electric communication system comprising a plurality of stations, means at one of said stations for sending an auxiliary preliminary signal for conditioning for reception the apparatus at another station to which the trans-

mitted main signals are intended to be sent and an auxiliary following signal for restoring to normal the apparatus of said station, and means entirely under the control of the main signals for 5 controlling said means.

2. A communication system according to claim 1 wherein the auxiliary signals are in the form of code signals and switching means are provided which are responsive only to said code signals for conditioning said apparatus.

3. In an electric communication system comprising a plurality of stations, means at one of said stations for sending an auxiliary preliminary signal in the form of coded impulses, means 15 at another station for responding to said coded impulses, means controlled by said last mentioned means for conditioning the apparatus at said other station for reception of the main signals, and means entirely under the control of 20 the main signals for controlling said first mentioned sending means.

4. A system according to claim 3, wherein the means for responding to coded impulses com-

prises a chain of relays so constructed and adjusted that the complete chain is operated only on receipt of a predetermined coded signal.

5. In a system as claimed in claim 3, the combination of a second means at said station for sending an auxiliary following signal in the form of coded impulses, means at said other station for responding to said coded impulses, means controlled by said last mentioned means for conditioning the apparatus at said other station for transmission of main signals therefrom, and means controlled by the cessation of main signals from said first mentioned station for controlling said sending means.

6. In a telephone transmission system, means under control of the voice currents for transmitting an auxiliary preliminary signal automatically with the commencement of talking and means for transmitting an auxiliary following signal automatically with the cessation of talking.
